UNITED STATES PATENT OFFICE.

JOSEPH E. DAWSON, OF DODSONVILLE, TEXAS.

CULTIVATOR FOOT.

1,427,075.

Specification of Letters Patent. Patented Aug. 22, 1922.

Application filed May 18, 1920. Serial No. 382,241.

To all whom it may concern:

Be it known that I, JOSEPH E. DAWSON, a citizen of the United States, residing at Dodsonville, in the county of Collingsworth 5 and State of Texas, have invented new and useful Improvements in Cultivator Feet, of which the following is a specification.

The object of the invention is to provide a simple inexpensive and efficient means for 10 mounting a standard upon the cultivator bracket or clamp so as to permit of the adjustment of the cultivator shovel to operate either in a straightforward direction or at an angle to either side, so as to throw the 15 soil either to the right or to the left, and at any desired depth, and with these objects in view the invention consists in a construction and combination of parts of which a preferred embodiment is shown in the accompanying drawings, wherein:

Figure 1 is a side view of a device arranged in the operative position.

Figure 2 is a sectional view of the same taken on a vertical plane.

25 Figure 3 is an elevation of a portion of the standard to show the arrangement of the seats or depressions therein for engagement by the locking bolts.

The standard 10 is revolvably and adjustably fitted in a guide opening 11 formed in 30 the head 12 at the lower end of the bracket 13, said guide being intersected by a threaded opening 14 in which is fitted the correspondingly threaded shank 15 of a locking 35 bolt having the cross handle 16 disposed within convenient reach of the operator for adjustment from time to time to secure the standard in the proper position.

The said standard is provided with a longitudinal series of seats or depressions 40 for the reception of the inner tapered or reduced extremity of the locking bolt to provide for varying the adjustment of the standard longitudinally to control the depth 45 of the shovel carried thereby and at each side of the said longitudinal series of seats or depressions are auxiliary seats or depres-

sions 18 disposed in angular relation with the longitudinal series of seats, and adapted respectively to be engaged by the inner tapered or reduced end of the locking bolt to hold the standard in a position to direct the shovel either to the right or to the left according to the direction in which the operator desires to throw the soil.

Obviously in order to vary the adjustment either angularly or longitudinally of the shovel it is only necessary to loosen the locking bolt sufficiently to disengage the reduced extremity therefrom from the seat or depression in which it is engaged, and turn the standard in the desired direction, whereupon the return of the locking bolt to its normal position will cause it to reengage the proper seat or depression of the standard 60 and rigidly and substantially hold the standard with the shovel carried thereby in the preferred position. It is obvious that not only can this change in adjustment be effected readily and quickly, but in the locked 65 position the standard is held firmly against accidental displacement due to strain or vibration, and the strength of the standard is not materially modified by reason of the provision in the surface thereof of the seats 70 or depressions necessary for the engagement of the extremity of the locking bolt.

Having described the invention what is claimed is:

The combination with a cultivator bracket 80 provided with a guide eye, having a threaded opening therein, of a standard slidably mounted in said eye, provided with a longitudinal series of depressions and also having a plurality of auxiliary seats disposed in 85 angular relation to the first mentioned depressions and a cross handle having a reduced threaded end engaging the threaded opening in said eye and adapted for selective engagement with said seats or depressions.

In testimony whereof I affix my signature.

JOSEPH E. DAWSON.
